United States Patent Office.

D. D. CODDING, OF NORTH ATTLEBOROUGH, MASSACHUSETTS.

Letters Patent No. 100,504, dated March 8, 1870.

IMPROVEMENT IN BRACELETS.

The Schedule referred to in these Letters Patent and making part of the same

To all whom it may concern:

Be it known that I, D. D. CODDING, of North Attleborough, in the county of Bristol, and State of Massachusetts, have invented a new and useful Improvement in Bracelets; and I do hereby declare that the following is a full, clear, and exact description thereof, which will enable others skilled in the art to make and use the same, reference being had to the accompanying drawings, forming part of this specification.

This invention relates to a new and useful improvement in bracelets for ladies' wear, whereby they are made lighter, more durable, more desirable, and cheaper than they have hitherto been; and

It consists in making the body of the bracelet of two semicircular pieces of wood, arranged and confined together as hereinafter more fully described.

In the accompanying drawing—

Figure 1 represents a view of a bracelet constructed according to my invention.

Figure 2 is an end view of one of the parts, showing the cross section.

Similar letters of reference indicate corresponding parts.

A and B are two semicircular or elliptical pieces of wood, which form the body of the bracelet, connected together by means of an elastic band, c.

In the outer surface of the pieces A B is a semicircular groove, d, which is covered by a metallic band, e, which is semicircular in cross section, but conforms

to the shape of the parts A B, as seen in the drawing.

The ends of these bands e e are confined at the ends of the parts A B by means of metallic clasps f.

The semicircular groove in the parts A B and the semicircular bands e form a tube around the bracelet, as seen in fig. 2, in which the elastic band c is placed, and which allow the parts A B to be rigid and formed of two pieces of wood, and to expand and contract as desired.

I am aware that short pieces of wood have been strung upon an elastic band or elastic cord for joining a bracelet before; but I am not aware that a bracelet has been before made by joining and combining two pieces of wood in the manner shown and described. Ebony or any of the dark-colored woods may be used, thus making the bracelet light in weight as well as in cost, while the contrast with gold is inviting and beautiful.

Having thus described my invention,

I claim as new, and desire to secure by Letters Patent—

Forming the body of a bracelet of two pieces of wood, as seen at A B, substantially as described.

D. D. CODDING.
